ANGUS S. MACDONALD, OF GREAT NECK STATION, NEW YORK.

METHOD OF MAKING TUBING.

1,321,530.

Specification of Letters Patent. Patented Nov. 11, 1919.

Application filed September 7, 1916. Serial No. 118,800.

To all whom it may concern:

Be it known that I, ANGUS S. MACDONALD, of Great Neck Station, county of Nassau, and State of New York, have invented certain new and useful Improvements in Methods of Making Tubing, of which the following is a specification.

This invention relates to a method of making tubing and has for its primary object 10 the provision of an improved method which is simple in character, and economical in operation and which secures uniformity and superiority of product.

The foregoing, together with such other 15 objects as may hereinafter appear, or are incident to my invention, I attain by means of a method and apparatus illustrated in the accompanying drawing wherein:

Figure 1 is a longitudinal section through 20 a draw bench showing one of the steps of my improved process; and Figs. 2 and 3 are sectional views illustrating the parts of the apparatus in different positions.

The invention is particularly useful in 25 connection with tube drawing manufacture, and it contemplates a heat treatment of the metal under control, and in such manner as to eliminate the formation of scale or corrosion, and warping and distortion, as well 30 as the elimination of certain steps in the customary methods pursued in manufacturing drawn tubing which involve considerable delay and labor.

In the manufacture of drawn tubing it 35 is customary to heat and pierce the billet and pass it a number of times through dies in order to form a tube, and thereafter the tube is given a number of passes either in hot or in cold condition, and the present invention has to do primarily with the final 40 steps in the formation of the tube. For example, after the tube is given its last pass, and while it is still in the draw bench, and under tension, as will be further pointed 45 out, I simultaneously heat all of the metal to a uniform temperature and eliminate the strains which are incident to the drawing process, particularly where the tube is cold drawn. I accomplish this by attaching a 50 pair of removable terminals to the tube adjacent the ends thereof and passing an electric current through the tube, the internal resistance to the current serving to uniformly and simultaneously heat all of the 55 particles of metal. Thereafter I suddenly cool the metal by quenching or cooling baths,

such for example as by the application of cooling liquids or fluids, after which the tube is cut off and is in finished condition.

Referring now particularly to Fig. 1, it 60 will be seen that I have therein illustrated a standard form of draw bench A which may be of any preferred type. The draw chain and the power means have not been shown, but it will be understood that such 65 means has been utilized in drawing the tube 7 through the die 8, suitably mounted at one end of the draw bench, and over the mandrel 9, which is supported in any suitable manner, as by a draw bench extension 70 (not shown). After the tube has thus been drawn, I provide a compensating means for placing the draw jaws 10 under tension, so that the tube 7, while placed under tension, may nevertheless freely expand without 75 warping and distortion during the heating step, and likewise contract when the metal is quenched. As one means for securing this result I employ a heavy weight 11 which is adapted to be attached to the draw jaws 80 10 by means of a cable 12 passing over a pulley 13. Two removable terminals or pole members 14 and 15 are detachably fastened on the tube 7, adjacent the ends thereof, and current is passed through the tube 85 7 from a dynamo 16 or other suitable source of current, through a transformer 17. Control of the heat is obtained in any suitable manner, as for example by means of the rheostat 18. As one means of quenching the 90 tube after it has been heated, I provide a tubular framework 19 which is suspended above the draw bench and is adapted to be lowered into the position shown in Fig. 2. A quenching element, such as oil is supplied 95 by this tubular framework in such manner as to make a substantially uniform application of the quenching material to the tube.

From the foregoing it will be seen that 100 my improved process may be briefly summarized as follows. After the tube has been drawn and while it is under a compensating tension, it is uniformly heated throughout, the heat being entirely under control, and then it is quenched and tempered, after 105 which the tube may be cut off and is in finished condition. By this improved process, I avoid the necessity of removing the tube to a heating furnace, in which heat is externally applied, and which is therefore not uniformly applied. The heating in addition to 110 eliminating the strains of the drawing op-

eration; prevents the formation of scale and oxidation and consequent metal losses because of the short period required for the heating, and at the same time warping or distortion is likewise prevented. Since the heating is entirely under control, and since the heating is uniform throughout the tube, it will be seen that uniformity of product is secured, the superiority of the product being further enhanced by reason of the fact that the heating and quenching are accomplished while the tube is under some measure of tension. The physical qualities of the metal can thus be determined and in addition a corrosion resisting surface can be obtained by the use of suitable quenching materials. In addition to obviating the necessity for removal to a heating furnace, I am enabled to dispense with the pickling baths which are necessary to remove scale and corrosion. My process also prevents de-carbonization of the metal.

It will be obvious that in certain cases it may be desirable to heat and quench the metal previous to the last pass, and also that various modifications of the method

and also of the particular apparatus shown and described may be made without departing from the spirit of my invention as set forth in the claims, as for example the die and draw jaws may be utilized as the terminals and cooled by water or other means. It will also be apparent that my invention is equally applicable to the drawing of steel in other forms, such as rods and bars, and therefore that the term tubing employed herein is used in a broad sense.

I claim: —

1. The process which consists in drawing a tube, placing it under tension and heating it, cutting off the heat, and while under tension quenching it *in situ*.

2. The herein described process of making tubes which consists in drawing a tube, in heating all portions of the tube substantially simultaneously and uniformly while in the drawing apparatus, in quenching the tube *in situ*, and in removing the tube.

In testimony whereof, I have hereunto signed my name.

ANGUS S. MACDONALD.
